UNITED STATES PATENT OFFICE.

ELISHA HAMLIN OSBORN, OF SAUK CENTER, MINNESOTA.

TELEPHONE-SIGNAL.

1,141,823.

Specification of Letters Patent.

Patented June 1, 1915.

Application filed March 5, 1914. Serial No. 822,708.

To all whom it may concern:

Be it known that I, ELISHA HAMLIN OSBORN, a citizen of the United States, residing at Sauk Center, in the county of Stearns and 5 State of Minnesota, have invented certain new and useful Improvements in Telephone-Signals; and I do hereby declare the following to be a full, clear, and exact description of the invention, such as will enable others 10 skilled in the art to which it appertains to make and use the same.

This invention relates to new and useful improvements in telephone signals and has for its principal object to provide a means 15 to signal a plurality of independent telephones simultaneously.

Another object of this invention is to provide a device which is particularly adapted for country communities having volunteer 20 fire corps to signal the inhabitants of the community in case of fire or similar accident.

A further object of the invention is to provide a device by means of which a number 25 of telephones may be cut in simultaneously in order that a general message may be delivered, thereby eliminating the necessity of calling each person individually and repeating the announcement.

30 A further object of this invention is to provide a simple and effective device by means of which a general alarm may be given from either the telephone operating switch-board, a night watchman's switch, or 35 any other desired point.

With these and other objects in view as will become more apparent as the description proceeds, the invention consists in certain novel features of construction, combination 40 and arrangement of parts as will be hereinafter more fully described and claimed.

For a complete understanding of my invention, reference is to be had to the following 45 description and accompanying drawings, in which—

Figure 1 is a view of a device constructed in accordance with this invention, showing the interior mechanism of the invention, the 50 same being partly in diagram to illustrate the method of wiring, Fig. 2 is a detail view of the contact for cutting in the telephone ringing circuit, and Fig. 3 is a detail view of one side of the magneto which is used for 55 ringing purposes.

Referring in detail to the drawings by

numerals, 1 designates a casing in which the several elements which are used in this invention are adapted to be contained. This casing 1 is provided with a bottom 2 and 60 false bottom 3 upon which the magneto, designated generally by the numeral 4, rests. A suitable shelf or similar support 5 is arranged within the casing and is so arranged as to support the battery 6 which is adapted 65 to furnish power for the operation of the device. The magneto above referred to is preferably of the ordinary type and is provided at each end with the bearing members 7 and 8 in which the drive shafts 9 and 10 70 are journaled. The shaft 11 carrying the armature 12 of the magneto is also journaled in the support, as shown in Fig. 3, and one end of this shaft is provided with the spur gear 13, which is driven by the gear wheel 75 14 carried on the shaft 10 which in turn is driven by the spur gear 15 carried in the shaft 10. A gear wheel 16 is secured to the shaft 9 and meshes with the gear wheel 15 and is arranged to drive the same when the 80 shaft 9 is rotated. A suitable winding drum 17 is secured to the end of the shaft 9 opposite the gear wheel 16 and is arranged to receive the flexible member 18 which winds on said drum, as clearly shown in Fig. 3. A 85 suitable weight or similar driving device is secured to the free end of the flexible member 18 and is adapted to drive the shaft 9 when the device is set in operation. A suitable lug 20 is secured to the gear 16 and is 90 arranged to engage the lug 21 which is carried on the free end of the lever 22. This lever 22 is pivoted to the frame, as at 23, and has formed integral therewith the angular extension 24, having in its free end the 95 adjusting screw 25 carrying a contact point 26.

A suitable contact spring 27 is secured to the frame and each of these contact elements 25 and 27 is provided with the binding posts 28 and 29 respectively. A suitable adjustable supporting member 30 is 100 slidable through the top of the casing, as shown in Fig. 1, and is provided with the thumb screw 31 by means of which the 105 same may be adjusted vertically with relation to the casing. This member 30 is provided at its lower end with the slot 32 through which the bar 22 is adapted to extend. Thus it will be seen that the armature 33 carried by the bar 22 may be 110 adjusted with relation to the core of the mag-

net 34, which will be more fully hereinafter described.

The magnet 34 above referred to is provided with the usual winding and has the core 35 extending centrally therethrough. This core 35 is arranged to come in direct alinement with the armature 33 in order that said armature may be drawn toward the core when the magnet is energized. A pair of binding posts 36 and 37 are arranged to form connection with the magnets by means of which said magnets may be connected in circuit with the battery 6 and switches 38 and 39, each of which is provided with the contacts 40 and 41 and the fixed arms 42, which are connected to the wires 43 and 44 to the binding post 45 of the battery 6. The opposite terminal of the battery is connected by means of the binding post 46 to the wire 47. After the current has passed through the magnet 34, the same will pass through the binding post 36 to the wire 48 and into the wire 47 which will carry the same back to the binding post 46 of the battery 6, thereby completing the circuit through the magnet 34.

The wire 47 coming from the binding post 46 of the battery 6, is extended, as at 51, and terminates at the magnet 52 in the binding post 53. The opposite binding post 54 has connected thereto the wire 55 which is connected, as at 56, to the wire 57, the terminals of which are connected to the contact point 41. The magnet 52 is provided with the core 58 which is arranged to coöperate with the armatures 59 to lift the lever 60 which is pivoted, as at 61, to the frame 2 of the device. A rod 62 is pivotally secured to the lever, as clearly shown in Fig. 1, and said rod is provided at its lower extremity with the screw threads which are arranged to coöperate with the turnbuckle 63, the use of which will appear as the description proceeds. A suitable cam 64 is carried by the shaft 9 and is adapted to rotate therewith. Said cam is arranged to engage the free end of the lever 60 to force the same upwardly when the magnet 52 is not energized. The opposite terminal of the turn-buckle 63 is operatively connected with the rod 65 which terminates at its lower extremity in the connections 66 and 67, the use of which will appear hereinafter. A suitable insulating turn-buckle 68 is interposed between the connections 66 and 67 and is arranged to insulate the said connections from each other. This insulating turn-buckle 68 is arranged to adjust the connections 66 and 67 with relation to each other to insure the proper contact of the bus bars, which will be more fully hereinafter described.

Connected to the binding posts 28 and 29 I provide the wires 69 and 70, the opposite terminal of the wire 69 is connected to

the magneto by means of the binding post 71, while the terminal of the wire 70 opposite the binding post 29 is connected, as at 72, to the levers 73 carrying the bus bar 74, as clearly shown in the drawings. The levers 73 are extended, as clearly shown in Fig. 1, and are provided with the connections 75 by means of which the connecting bar 76 is held in proper position. This connecting bar 76 extends through the connection 67 and thereby pivotally secures the levers 73 to the bar 65.

A plurality of bars 77 are spaced from each other, and are connected to the telephone switch-board 78 by means of the cable 79, which carries a plurality of connecting wires 80 terminating in the telephone circuit carrying the cables 81.

A second set of bars similar to the bars 77 are provided and are connected by means of the cable 82 by means of the wires 83 which are connected to the telephone switch-board and terminate in the cables 84 carrying a telephone connection, as clearly shown in Fig. 1. A pair of levers 85 are pivoted, as at 86, to the casing and have secured adjacent their free ends the bus bar 87 which is arranged to contact with the second set of bars to throw the telephones in circuit when the device is operated. Each of these bars 85 is provided with the connection 88 which is arranged to support the rod 89 passing through the connection 66 which pivotally secures the bars 85 to the rod 65.

A suitable wire 90 is connected to one of the levers 85 and the opposite terminal of said wire is connected to the binding post 91 carried by the magneto. Thus it will be seen that when the lever 22 is drawn upward by means of the magnet 34, the contact point 26 will engage the contact spring 27 and close the circuit from the magneto through the wire 69, binding post 28, contact arm 24, contact point 26, contact spring 27 to the binding post 29, from which the current will pass through the wire 70 to the lever 73, and when the lever is forced upwardly against the bars 77, the bus bar 74 will contact with the bars 77 and send the current through the several telephone ringing circuits back through the cable 84 to the switch-board 78 and cable 82 to the second set of bars, thence back through the levers 85 to the wire 90 and binding post 91, from which the current enters the magneto 4.

It will be apparent from the foregoing that in use when either of the switches 38 or 39 is thrown to the contact 40, the current will pass through the wire 44 to the wire 43 into the switch arm 42 through the contact 40, wire 49 to the branch wire 50 and into the magnet 34 through the binding post 37. After passing through the magnet, the current will pass through the binding post 36, branch wire 48 to the wire 47 and again

enter the battery through the binding post 46, thus energizing the core 35 of the magnet 34 and drawing the armature 33 carried by the lever 22 toward said core and releasing the lug 21 from behind the lug 22, thus permitting the weight 19 to descend and set the shaft 9 in motion. The rotation of the shaft 9 will drive the gear wheel 16 which in turn will turn the spur gear 15, driving the shaft 10 and causing the gear wheel 14 to revolve, which meshing with the gear wheel 13 on the shaft 11 will drive the armature 12 of the magneto and thus generate the current in the magneto which is used to ring the bells of the telephones. Simultaneously with the revolution of the wheel 16 and shaft 9, the cam 64 will revolve and raise the end of the lever 60, thus pulling upwardly on the bar 62, turn-buckle 63 and bar 65, thereby raising the levers 73 and 85 and bringing the bus bars 74 and 87 into engagement with the bars 77 and the similar bars which are connected to the cable 82 which terminates in the telephone switchboards 78, thus closing the circuit through the telephones simultaneously and permitting the current which passes from the magneto through the binding post 71, wire 69, binding post 28, contact arm 24, contact point 26, contact spring 27, and binding post 29 to pass through the wire 70 and into the cable 79 through the levers 73 and bus bar 74, while the current passes back to the magneto through the cable 82, the bus bar 87, levers 85 and wire 90 to the binding post 91 of the magneto. After the signal has been given, the switch arm 42 is swung to the contact point 41 which will throw the circuit from the battery 6 through the binding post 45 to the wire 44 into the wire 43, through the contact arm 42, contact point 41 to the wire 57 and joint 56 into the branch wire 55 from whence the current passes into the magnet 52 through the binding post 54. The circuit then passes from the magnet 52 into the binding post 53 through the wire 51 to the wire 47 and returns to the battery through the binding post 46. Thus it will be seen that the core 58 of the magnet will be energized which will draw the armature 59 carried by the lever 60 upwardly and thereby throw in the telephone circuit and permitting the operator to make any announcement over the wires that may be necessary.

In using this device it will be evident that the parties which it is desired to call, may be cut in on the line simultaneously and a single announcement may be made over the telephone which will be transmitted to all the phones in circuit, thus eliminating any necessity of repeating the announcement, and thus avoiding considerable loss of time.

While I have shown and described the preferred embodiment of my invention, it

will be understood that minor changes in construction, combination and arrangement of parts may be made without departing from the spirit and scope of the invention as claimed.

Having thus described my invention, I claim—

1. The combination with a telephone switch board and telephone circuit of a device of the character described, including a magneto, a plurality of bars connected in circuit with one terminal of a telephone switchboard, a second set of bars connected in circuit with the opposite terminal of the telephone switchboard, a bar adapted to connect all of the bars in one set simultaneously, a second bar adapted to connect all the bars in the second set simultaneously, a wire connecting one set of bars to the magneto, an automatic switch, a wire connecting the switch to the other set of bars, a wire connecting the switch and magneto, an electromagnet, a lever, said lever controlling the automatic switch, an armature on said lever and adapted to be attracted by the electro-magnet, a train of gears to operate the magneto, means to control the flow of electricity through the electromagnet, and electrically controlled means to throw all the telephone circuits in circuit simultaneously.

2. The combination with a plurality of telephone circuits of a device of the character described, comprising a magneto, a train of gears for operating said magneto, means to cause the gears to revolve, a cam carried by one of said gears, a power supply, an electromagnet in circuit with the power supply, a switch for controlling the operation of the electromagnet, a lever, a lug carried by one of said gears and adapted to engage the lever to hold the gear from rotation, a contact arm on the lever, a contact spring adapted to coöperate with the contact arm, a second electromagnet, a lever, the free end of said lever being adapted to be engaged by the cam on the gear wheel so that said lever will be raised when the gear wheel is rotated, the second mentioned electromagnet being adapted to attract the lever and also being in circuit with the power supply, means to control the energizing of the second mentioned electromagnet, and means controlled by the second mentioned lever to throw in the telephone circuits when either of the switches are operated.

3. The combination with a plurality of telephone circuits of a device of the character described including a magneto, means to control the operation of said magneto, a cam carried by the magneto controlling means, an electromagnet, a lever adapted to be attracted by said electromagnet, a contact arm on the lever, and a contact spring adapted to be engaged by the contact arm, means connected with the contact arm, contact

- spring and magneto, to throw in the telephone circuits, and means automatically and electrically operated to control the throwing in of the telephone circuits.
- 5 4. The combination with a telephone switchboard carrying a plurality of telephone circuits, of a magneto, means in circuit with the magneto to throw in the telephone circuits through the switchboard, a 10 weight operated mechanism to drive the magneto, electrically controlled means to automatically release the weight operated means and set the magneto in operation, an automatic switch operated by the electrically controlled means to cut in the magneto circuit, a cam carried by the magneto driving mechanism, a lever controlled by the cam, an armature on the lever and adapted to be attracted by a second electromagnet 15 and means connecting the lever with the telephone circuit controlling means to cut in the telephones and give a signal thereon.
5. The combination with a plurality of 20 telephone circuits of a device of the character described, a magneto, a train of gears to set said magneto in operation, a stop carried by one of said gears, a cam carried by one of said gears, a lever, an electromagnet,

an armature carried by said lever, an extension formed at the free end of the lever, said armature being adapted to be attracted by the electromagnet, a contact arm formed on the lever, a contact spring coöperating with the contact arm and adapted to be engaged when the lever is raised, a second electromagnet, a second lever, the free end of the second mentioned lever being adapted to be engaged by the cam on the magneto operating mechanism, an armature on the second mentioned lever and adapted to be attracted by the second mentioned electromagnet, means to cut in the plurality of telephones, means to operate the telephone cutting in means, and wires connecting the magneto through the contact arm and contact spring 45 with the telephone cutting in means to complete a circuit through the cutting in means to the telephones and thereby ring the bells on each of the telephones.

In testimony whereof I affix my signature 50 in presence of two witnesses.

ELISHA HAMLIN OSBORN.
